TYPEWRITING MACHINE

Filed Aug. 11, 1928

FIG. I.

FIG.2.

FIG. 3.

INVENTOR:

At Edgar Goetz
BY B. J. Hickney
ATTORNEY.

UNITED STATES PATENT OFFICE

A EDGAR GOETZ, OF FAR ROCKAWAY, NEW YORK, ASSIGNOR TO UNDERWOOD ELLIOTT FISHER COMPANY, OF NEW YORK, N. Y., A CORPORATION OF DELAWARE

TYPEWRITING MACHINE

Application filed August 11, 1928. Serial No. 299,087.

The present invention relates to means for illuminating the interior of sound-deadening cases for typewriting machines.

It is usual to provide a glass window in a sound-deadening case for a typewriting machine, through which typing may be viewed as it is performed. Occasionally light is reflected in an objectionable way from this glass window into the eyes of the operator. To prevent this reflection, a blind or shade of the kind disclosed in the patent to G. W. Campbell 1,526,962 is sometimes mounted over the window. In some cases, this shade makes the interior of the sound-deadening case objectionably dark, especially when the lighting in a room is deficient.

It is a feature of the present invention to mount electric lamps inside a sound-deadening case and provide means for reflecting the light from the lamps so as to satisfactorily illuminate the printing field of the platen without interfering with the operation of the typewriting machine.

Another feature resides in the employment of the shade for carrying a reflecting mirror which co-operates with lamps for illuminating the interior of the case.

In carrying out my invention, an electric lamp is mounted in the sound-deadening case at each side of the typewriting machine forwardly from the carriage. A mirror is mounted in front of each lamp and is effective for reflecting light from it rearwardly to the printing field of the adjacent end portion of the platen, when said portion extends beyond the side of the machine. A mirror is also mounted on the underside of the shade and is effective to reflect light from both lamps to the portion of the platen disposed between the sides of the typewriting machine as well as each end portion of the platen. This arrangement provides desirable glareless illumination.

It is another feature of the invention to provide each lamp and its associated reflecting mirror as a compact unit having means for attaching it to the sound-deadening case.

A further feature of the invention resides in making certain of the mirrors effective for diffusing light to further reduce glare.

Other features and advantages will hereinafter appear.

In the accompanying drawings,

Figure 1 is a perspective view of an Underwood typewriting machine enclosed in a sound-deadening case having my invention applied thereto. A portion of the case is broken away for showing an element of my invention more clearly. 55

Figure 2 is a perspective view of an electric lamp unit used in practicing my invention. 60

Figure 3 is a cross-sectional view, front to rear, through the structure shown in Figure 1, and illustrates how light rays from lamps mounted inside of the sound-deadening case may be reflected to illuminate the platen. 65

In an Underwood typewriting machine, generally designated as 10, types 11 strike 70 against a platen 12. To diminish the noise resulting from impacts of the types against the platen, it is common to place the machine 10 in a sound-deadening case generally designated as 14, which may include a lower body portion 15 and a cover 16 mounted thereon by hinges 17. The body portion may have lateral extensions to permit travel of a platen-carriage 18 in each direction. The sound-deadening case may be of a well-known construction and it is not deemed necessary to describe it in detail herein, for an understanding of the present invention. A usual sound-absorbing lining 19 of a material like felt may be applied to the inside 85 surface of the case at all points except as hereinafter noted.

In order to line-space the platen 12 and return the platen-carriage 18, a line-space lever 20 extends from the machine through a slot opening 21 at the front of the casing between the body portion 15 and the cover 16. A carriage-return finger-piece 22 and a carriage-release lever 23 of a well-known construction may also extend through the opening 21 which is positioned a short distance below a usual front bar 24 of the carriage 18. The finger-piece 22 and the lever 23 are attached to this front bar, and the line-space lever passes over it closely adjacent 100

thereto, and all of these parts extend forwardly and curve downwardly to pass through the slot opening 21 (see Figure 3).

To reduce the width of the slot opening to a minimum that will permit the free lateral travel therein of the lever 20, a usual felt strip 25 is fastened by an angular plate 26 to the inside of the cover 16 so as to extend along the opening at the upper side thereof.

10 A strip of felt 27 is employed to co-operate with the strip 25 and may be held against the inside of the body portion adjacent the opening 21 by a plate 28 which may be longitudinally bent so as to have a substantially inverted Y cross-section such as is shown in Figure 3. It will be noted that the strip 27 is disposed between an upturned leg 29 of the Y-plate 28 and is braced by an arm 30 of the latter, which engages against an upper portion of the felt lining 19 disposed against the inside of the body portion 15.

20 To permit typing on a work-sheet 31 to be viewed by the operator as the typing is performed, a view-opening 32 is provided in the cover 16 and is enclosed by a pane of glass 33 which may be fastened to the cover in a well-known way.

In some cases, typewriters equipped with a sound-deadening case have been used where 30 light rays were reflected from the panes of glass 33 into the eyes of the operator, which was objectionable. To prevent this reflection, a blind or shade 34 of the same construction as disclosed in the patent to G. W. 35 Campbell 1,526,962 may be supported on two arms 35 which are pivotally mounted on the cover 16. The blind may be made of a piece of sheet-metal 36 having a concavo-convex cross-section (see Figure 3).

40 In using a typewriter enclosed in a sound-deadening case having a blind of the kind mentioned above, it sometimes happens that the lighting arrangement of a room is such that the interior of the sound-deadening case is not sufficiently illuminated for good work. For providing satisfactory illumination in such cases, or in any sound-deadening case where more illumination is needed, it is a feature of my invention to mount two electric lamps, generally designated as 40, inside the sound-deadening case, one at each side of the typewriter in the extensions of the body portion 15. Since the depth of the space at each side of the typewriting machine for receiving such lamps is shallow, I 50 prefer to employ lamps having cylindrical bulbs 41 of small diameter relative to their length. Such lamps can be bought in the open market. Each bulb is secured in a usual socket 42 which may be fastened by soldering, or in any other suitable way, to an end wall 43 of a lamp housing, generally 55 designated as 44. The housing may have a floor 45, a rear wall 46, which are integrally joined to the end wall 43, and a front wall

47 which extends above the rear wall and which integrally joins the floor. An integral bracing lug 48 on the end wall may be bent to lie against the forward side of the front wall to which it may be fastened as by riveting.

5 The housings 44 may each have means for detachably hanging it on the body portion 15, which means may consist of two hanger members 50 whose lower ends 51 extend under the floor 45 to be soldered thereto adjacent each end. The upper end of each hanger member may be bent down to form a hook portion 52 which may engage snugly over the upper end of the inverted leg 29 of the Y-plate 28 and pass between the leg and the felt strip 27. The lower end of the hangers 50 may rest against the felt lining 19.

10 To guard against glare, the rear wall 46 stops light from the lamp bulb from going directly to the platen 12. To convey the light indirectly from the bulb to the platen a mirror 55 is disposed under the bulb to rest on the floor 45 and another mirror 56 is disposed in front of the lamp bulb and extends from the first-named mirror upwardly a short distance past the top of the bulb in a substantially vertical plane, and then curves to the rear extending partly 15 over the lamp bulb 41. The top edge of the curved portion of the mirror will be disposed a short distance below the path of the curved portion of the line-space lever 20. The mirrors 55 and 56 may be fastened to the housing 44 by integral lugs of the same which extend past the edges of the mirrors and are bent over against their faces. Also the upper end of the front wall may be bent over the upper edge of the mirror 56.

15 For a purpose to presently appear, the work face of each of the mirrors 55 and 56 will preferably be formed with a series of low ridges or beads 57 which are disposed transversely to the length of the bulb 41. The height of a ridge 57 will preferably be small relative to its width, and the top of the ridge will preferably be very slightly rounded. This construction will provide a series of shallow grooves 58 between two adjoining ridges. The rounded ridges serve to diffuse the light, and to reflect it over a wider area than would occur if the mirrors were plain.

20 As illustrated in Figure 3, certain rays of light generated in the lamp bulb 41 will strike against the curved portion of the mirror 56 and will be reflected to the printing field of the platen 12 when an end portion of the latter extends beyond the side 25 of a main frame 59 of the typewriting machine.

25 Since each lamp bulb 41 and its curved reflecting mirror 56 are positioned at one side of the main frame 59 and slightly be-

low the top of the latter, light reflected by the mirrors 55 and 56 may not satisfactorily illuminate the portion of the platen disposed between the side of the main frame 59. To illuminate the last-mentioned portion of the platen by the above-mentioned lamps, there is provided a mirror-like reflecting plate 60 which may be fastened, as by screws, to the under side of the blind 34, the plate having a transverse concavo-convex curvature substantially the same as the blind, and thereby may be mounted compactly thereagainst. Since the concave side of the mirror plate is turned down, it will be apparent, from inspection of the dia-grammatic representations of the light rays from Figures 1 and 3, that light rays from the lamps 40 will be reflected to every portion of the platen and the printing field thereof.

The mirror plate 60 will preferably be of thin sheet-metal having its lower face highly polished. The blind 34 may be held by friction in any work position in which it may be set to have the mirror plate 60 co-operate with the lamps 40. It can be readily seen that certain light rays from the lamps will strike against the mirror 55 on the floor of the housing and be reflected to the mirror plate 60 and thence to the platen. For bringing electric current to the lamps 40 an ordinary insulated electric light cord 61 may enter the body 15 through a hole 62 adjacent the bottom of the body and have two branches, one leading to each socket 42 to be connected therewith in the usual way.

Each socket is disposed on the opposite side of the associated lamp from the type-writing machine, which arrangement is convenient for bringing the electric conducting wires to the sockets without interfering with the functioning of the typewriting machine. This arrangement also disposes the free unattached end of the bulbs 41 in position to effect maximum illumination of the typewriting machine.

It will be noted (see Figure 2) that the lamp 40, the housing 44, the mirrors 55 and 56, and the hanger members 50 are assembled as a unit which can be readily attached to a sound-deadening case without change in the latter except for making a hole for the cord 61 to enter the case.

Variations may be resorted to within the scope of the invention, and portions of the improvements may be used without others.

Having thus described my invention, I claim:

1. The combination with a typewriting machine and a sound-deadening case having a body portion, a cover for the same, a glass-covered view opening in said cover and a glare-preventing blind for said opening, of an electric lamp mounted in said case at

each side of said machine and in front of the carriage of said machine, a mirror at the front of each lamp for reflecting light therefrom to the adjacent end portion of the platen of said machine extending out beyond the side edge of the same, and a mirror fastened to the under side of said blind, which is effective to reflect light from said lamps to the central portion of said platen between the sides of said machine.

2. The combination with a sound-deadening case for a typewriting machine, of a lamp positioned for illuminating the interior of said case, means for preventing light from said lamp passing directly to the printing field of the platen of said machine, and means for reflecting the light of said lamp to said printing field, whereby glare from said lamp is prevented.

3. The combination with a sound-deadening case for a typewriting machine, of two electric lamps, means for mounting said lamps in said case, one lamp disposed at each side of said machine out of the path of the carriage of said machine, and means for reflecting the light from said lamps to illuminate all parts of the printing field of said machine.

4. The structure described in claim 4, characterized by said case having a stationary body portion and a displaceable cover hinged thereto, and further characterized by the lamps being mounted on said body portion out of engagement with said displaceable cover.

5. The combination with a typewriter sound-deadening case having a body portion with lateral extensions to permit travel of the carriage of the typewriter, and a cover for said body portion having a glass-covered view opening, of two electric lamps in said case disposed against the front wall of said body portion, one at each side of the main frame of the typewriter in said extensions, reflecting devices in said case effective for reflecting the light of said lamps to end portions of the platen of said typewriter when said end portions extend beyond said main frame, and reflecting means supported on said cover for reflecting the light of said lamps upon the portion of said platen between the sides of said main frame.

6. The structure described in claim 5, characterized by a glare-preventing shade for the glass-covered window opening, and a reflecting mirror fastened to the under side of said shade for reflecting the light from said lamps to said platen.

7. The combination with a sound-deadening case for a typewriting machine, of a lamp effective for illuminating the interior of said case, means for preventing light from said lamp passing directly to the printing field of said machine, and mirrors positioned for reflecting the light from said lamp to

the printing field, said mirrors having means including rounded ridge portions for diffusing the light from said lamp, whereby to reduce glare.

8. An illuminating unit for a sound-deadening case for a typewriting machine including a housing, instrumentalities for detachably fastening said housing to said case on the interior of the latter, an electric lamp socket fastened to said housing at the interior thereof, an electric lamp engaging in said socket, and a mirror at one side of said lamp effective for reflecting light from said lamp toward the opposite side and over said lamp, said housing being arranged to stop the light passing directly from said lamp in the direction of the reflected light.
9. The structure described in claim 8, characterized by the mirror at the side of the lamp extending above said lamp, and having its upper portion curved partly over said lamp.

10. The combination with a casing for a typewriting machine having a platen and a carriage, said casing having a stationary body-portion and a displaceable cover hinged thereto, of two electric lamps mounted in said body-portion of the casing, one lamp disposed at each side and in front of the carriage of the machine, the cover of said casing having a glass window for observing the work during typing, and means for reflecting the light from said lamps to illuminate the printing field of said machine, including means effective to receive light-rays from said lamps through said window and reflect them through the window again to the platen of the machine.

11. The combination with a typewriter-casing having a body-portion with lateral extensions to permit the travel of a typewriter-carriage and a cover for said body-portion having a glass window therein, of two electric lamps in said casing disposed one at each side against the front wall of said body-portion in said extensions, devices in said casing effective for reflecting the light of said lamps to a platen of a typewriter when the end portions thereof extend beyond the main frame, a glare-preventing adjustably-mounted shade associated with the window, and a reflecting mirror positioned at the underside of the shade having a curvature effective to reflect light to the platen.

12. An illuminating unit for a typewriting-machine casing including a housing, means for detachably attaching said housing to the interior of the casing, an electric lamp mounted in said housing, a mirror located at one side of said lamp, effective for reflecting light therefrom toward the opposite side thereof, and over said lamp, means included in said housing to prevent the light from passing directly from said lamp in the

direction of the reflected light, said mirror extending above the lamp and having an upper curved portion partly overhanging the lamp, and corrugations on said mirror for diffusing the light of the lamp as it is reflected to the interior of the casing.

13. The combination with a casing for a typewriting machine including a cover, of illuminating means within said casing for lighting the interior of the same, and means including a reflector on said cover effective to reflect light from the illuminating means to the printing field of said machine.

14. The combination with a casing for a typewriting machine including a cover, of a lamp within said casing for illuminating the interior of the same, and means, including a reflector on said cover and a light barrier between the lamp and the machine effective to permit reflected light, and only reflected light, to reach the printing field of said machine.

15. The combination with a casing for a typewriting machine including a cover, of a lamp within said casing for illuminating the interior thereof, and means including a reflector associated with the lamp, a reflector on said cover and a light barrier between the lamp and the machine, effective to permit reflected light and only reflected light to reach the printing field of said machine.

16. The combination with a casing for a typewriting machine including a stationary member to receive the machine and a cover for the same, of illuminating means within said stationary member of the casing, and means on said cover effective to reflect the light from the illuminating means to the printing field of said machine.

17. The combination with a casing for a typewriting machine including a stationary member to receive the machine and a cover for the same, of illuminating means within said stationary member of the casing, a light barrier between said means and the machine, and means on said cover to reflect light from the illuminating means to the machine.

A EDGAR GOETZ.
